SWEATER OR THE LIKE

Henry Rubin, University Heights, Ohio, assignor to Ohio Knitting Mills, Cleveland, Ohio, a corporation of Ohio

Application September 7, 1949, Serial No. 4,897

Term of patent 7 years

(Cl. D3—4)

To all whom it may concern:

Be it known that I, Henry Rubin, a citizen of the United States, residing at University Heights, county of Cuyahoga, and State of Ohio, have invented a new, original, and ornamental Design for a Sweater or the like, of which the following is a specification, reference being had to the accompanying drawings, forming a part thereof.

Fig. 1 is a front view of a sweater, showing my new design.

Fig. 2 is a rear view thereof.

I claim:

The ornamental design for a sweater or the like, substantially as shown.

HENRY RUBIN.
